UNITED STATES PATENT OFFICE.

GEORGE W. MELOTTE, OF ITHACA, NEW YORK.

REFRACTORY BED FOR SOLDERING.

SPECIFICATION forming part of Letters Patent No. 433,252, dated July 29, 1890.

Application filed June 14, 1889. Renewed February 12, 1890. Serial No. 340,155. (No model.)

To all whom it may concern:

Be it known that I, GEORGE W. MELOTTE, a resident of Ithaca, in the county of Tompkins and State of New York, have invented 5 certain new and useful Improvements in Refractory Beds for Soldering; and I do hereby declare the following to be a full, clear, and exact description of the invention, such as will enable others skilled in the art to which it applies 10 pertains to make and use the same.

The invention has relation to a refractory bed and attachments suitable for use with a blow-pipe for soldering and like purposes, and is an improvement upon devices described 15 in patents, Nos. 400,103 and 400,240, granted to me March 26, 1889; and its object is to improve the efficiency and facilitate the manufacture of such devices; and it consists in the matters hereinafter described and pointed out.

20 In the accompanying drawings, Figure 1 is a perspective view of my improved bed. Fig. 2 is a plan view of a modified form. Fig. 3 is a section on line $x-x$, Fig. 2. Fig. 4 is a perspective view of a bed provided with a rim. Fig. 5 is a similar view of a rectangular bed and rim, and Fig. 6 is a view of a detail.

25 Reference-figure 1 indicates a bed, which, according to the present improvement, is composed of successive layers of asbestos, which 30 may be made in band or ribbon form by weaving, braiding, or matting together in any known manner, or the fibers may be arranged, shaped, and pressed into the desired form and properly trimmed, if necessary, without 35 forming a band or the like. The successive lateral layers 2 2 2, of which the bed is composed, as shown in Fig. 3, may be formed either by bending back on itself a continuous ribbon in successive portions, or the ribbon 40 may be first cut in suitable lengths and the several pieces placed side by side to produce the bed. Upon two opposite sides of these layers side pieces 3, preferably of metal, are secured by bolts 4, which pass through 45 the bed and are riveted at each end. They may, however, be fastened by screw-bolts or other like means.

50 Wood instead of metal may be used for side pieces, and, if desired, a receptacle for the asbestos may be provided that surrounds the asbestos on all sides, as shown in Fig. 2.

One edge of one or both side pieces is pro-

vided with holes, sockets, or slots 5, to receive the foot or shank of a clamp 6, the free end of which is adapted to be lowered upon any 55 article it is desired to hold on the bed, and these clamps are preferably provided with a coil or other spring 7. Sockets for the reception of the clamps may be formed of loops or staples, as shown at 5'. It is also contemplated to provide for entering the foot of a clamp in a horizontal direction, as at 5''. In some cases sockets may be dispensed with and the clamp coiled about a fixed rod or other port, as shown at 5''. In this case the 60 end or foot of the clamp is continued down, so as to bear on the side of the stand or frame, as shown at 8. A clamp so secured can be moved laterally on its support, the coil serving both as a spring and as a means of attachment to the rod or other port affixed to the stand.

In Fig. 1 the side plates each are shown provided with a rib 9, in which are formed notches or openings 10 to receive and hold 75 the foot of a clamp. These notches, if made in dovetail form, as shown at 11, admit the clamp by insertion from above, and hold it very securely. At 12 are shown slots provided in the flange of the side pieces for the 80 reception of the clamps, which slots permit the sidewise adjustment of the same.

In Figs. 4 and 5, 13 indicates a removable rim or fire-guard adapted to retain heat on and over the bed. It absorbs heat which 85 would otherwise be radiated into the surrounding atmosphere, and it also interrupts or diverts air-currents which might otherwise have too great a cooling effect. This rim may be made either curved or rectangular in outline. It is provided with a break or notch 14, which may vary in size, or in some cases be entirely omitted and the rim made a continuous circle, or complete hollow square or other figure. 15 shows a clamp adapted to pass 90 over the rim or guard. The free ends of the clamp are variously fashioned, as indicated.

The general uses and capacities of the bed and some of the details of construction are described in the aforesaid patents, and further description thereof herein is unnecessary.

Having thus described my invention, what I desire to secure by Letters Patent is as follows:

1. A bed for soldering, made of pieces of as-

- bestus band placed side by side and secured between side plates, substantially as specified.
2. A refractory bed for soldering, made of straight pieces of asbestos band or ribbon placed side by side and between plates, said plates being secured together and upon the asbestos by bolts, substantially as specified.
3. A refractory bed for soldering, provided with side plates having a perforated flange, and a notched rib to receive and hold a clamp, substantially as specified.
4. A refractory bed for soldering, provided with side plates having a perforated flange, and a rib provided with a dovetail notch to receive and hold a clamp, substantially as specified.
5. A refractory bed for soldering, in com-

bination with a clamping device having a spring coil between its clamping end and its foot, said coil embracing a guide fixed to the frame of the bed, substantially as specified.

6. The refractory bed provided with a removable refractory open-topped rim and with an adjustable clamping device to hold the rim in place and in contact with the bed, substantially as specified.

In testimony whereof I have signed this specification in the presence of two subscribing witnesses.

GEORGE W. MELOTTE.
